REFRIGERATING APPARATUS

Lawrence A. Philipp, Detroit, Mich., assignor to
 Kelvinator Corporation, Detroit, Mich., a corporation of Michigan

Application April 10, 1933, Serial No. 665,271

10 Claims. (Cl. 62—116)

This invention relates to refrigerating apparatus, and more particularly to refrigerating apparatus of the compression type arranged for refrigerating large quantities of foods and for freezing large quantities of substances.

One of the objects of my invention is to provide an improved refrigerating system for freezing substances and for cooling circulating air in a refrigerator cabinet.

10 Another object of my invention is to provide in a refrigerator cabinet a relatively large heat capacity refrigerant evaporator for freezing large quantities of substances, and a relatively small heat capacity refrigerant evaporator for cooling circulating air in the food storage compartment of said cabinet, and to arrange for precooling a portion of the circulating air by the refrigerating effect of the large heat capacity evaporator and later cooling the air to the desired temperature 20 by the small heat capacity evaporator.

Another object of my invention is to employ forced convection means in a new and novel manner in the aforesaid refrigerating apparatus.

Another object of my invention is to provide 25 within a refrigerator cabinet an improved arrangement of and control for refrigerant evaporating means, which is arranged for operating without the collection of frost thereon or a slight film of frost is allowed to collect thereon during the on-phase of the refrigerating cycle and is melted off during the off-phase of the refrigerating cycle, while at the same time provisions are made for freezing substances, such as ice cubes and the like, and for cooling circulating air in the food storage compartment where- 30 by continuous refrigeration at substantially constant, predetermined temperatures is insured and the necessity of periodic inoperative conditions of the system for defrosting is avoided.

40 Other objects and advantages will be apparent from the following description, reference being had to the accompanying drawing.

In the drawing:

Fig. 1 is a front view in elevation of a refrigerating apparatus embodying features of my invention;

Fig. 2 is a vertical view in cross section of the refrigerating apparatus shown in Fig. 1 with a diagrammatic illustration of the refrigerant 50 condensing element removed from the cabinet; and

Fig. 3 is a view taken along the lines 3—3 of Fig. 1.

Referring to the drawing, numeral 20 designates, in general, a refrigerator cabinet having

insulated walls, including top wall 22, bottom wall 23, side walls 24, rear wall 25 and front wall 26. The cabinet 20 is provided with food storage compartments 30 and 32.

Within the cabinet adjacent the top wall 22 and between the storage compartments 30 and 32 there is disposed a refrigerant evaporating element 34. A metallic shield or shell 35 is arranged to cooperate with the top wall 22, rear wall 25 and a front cover plate or shield 36 to provide a low temperature compartment 37 and to isolate the evaporating element 34 from direct contact with the circulating air in the compartments 30 and 32. A pair of vertically extending, spaced apart baffles 38 are disposed on opposite sides of the shell 35 with their upper ends terminating below the top wall 22 of cabinet 20 and their lower ends terminating above the bottom wall 23 of the cabinet 20. The baffles 38 extend from the rear wall 25 to a front closure plate 36. By so locating the baffles 38, there is provided passages 41 and 42 on opposite sides of the shell 35, and a larger passage 44 is provided below the shell 35 between the baffles 38, rear wall 25 and the front cover plate 36.

Within the passage 44 there is disposed a relatively small heat capacity refrigerant evaporating element 46 which is supported by air deflectors and drip water conductors 48 which are secured on their upper ends to the baffles 38. A 55 drip receiver 49 is positioned on the bottom wall 23 of the cabinet 20 immediately below the lowermost ends of the drip water conductors 48 to receive the drip water from the evaporating element 46.

Preferably, the refrigerant evaporating element 34 is of relatively large heat capacity for freezing large quantities of ice cubes and the like and comprises, in general, a plurality of vertically spaced refrigerated shelves 50, which may 60 be of any suitable construction. The shelves 50 are connected to each other by means of conduits 51. The shelves 50 are rigidly secured in position by means of vertical metallic members 53. The shelves provide supports for ice making receptacles 55. Positioned at the uppermost part of the element 34 is a refrigerant accumulator 54.

The relatively small heat capacity refrigerant evaporator 46 comprises, in general, two looped 105 refrigerant conduits 56, which are, preferably, in the form of serpentine coils. Manifolds 58 and 59 are arranged to interconnect the inlets and outlets, respectively, of the two coils 56. In order to increase the heat transfer characteristics 110

of the element 46, I have provided a plurality of spaced apart heat absorbing fins 60 which extend over the conduits 56.

A refrigerant condensing element 62 is operationally connected to the evaporating elements 34 and 46 by means of a liquid supply conduit 63 and a vapor return conduit 64. The condensing element 62 comprises, in general, a compressor 66, motor 67 for operating the compressor, a condenser 68, and a high side float mechanism 69. The compressor withdraws gaseous refrigerant from the accumulator 54, compresses the gaseous refrigerant and delivers it to the condenser 68 wherein it is liquefied and from which it is delivered to the interior of the housing of the float mechanism 69. Liquid refrigerant is supplied to the elements 46 and 34 through the supply conduit 63 under the control of float mechanism 69.

20 Liquid refrigerant is first delivered to the element 46 whence it is delivered to the evaporating element 34 after first passing through a pressure responsive valve 72. The pressure responsive valve is provided for maintaining a pressure differential between the elements 46 and 34. 25 In view of the fact that the elements 34 and 46 are of the so called flooded type, the pressures therein will bear a direct relation to the temperatures therein. Thus, the pressure responsive valve 72 is provided for obtaining a temperature differential between said elements. The pressure responsive valve 72 may be of any suitable type, preferably of the type which includes a weighted valve proper (not shown) responsive to pressures of the refrigerant in the element 46. 30 By this arrangement, a temperature differential is obtained between the two evaporating elements 34 and 46.

35 Preferably, the condensing element is intermittently operated. In order to control the operation of the condensing element, I have provided a thermostatically controlled switch 80. To the switch 80 is connected a fluid containing thermostatic bulb 82 by means of conduit 84. 40 The bulb 82 is disposed in the food storage compartment 32 so that the expansion and contraction of the fluid contained therein will be influenced by changes in temperatures in the circulating air in said compartment to thereby control the operation of the switch 80 in response 45 to changes in temperatures of the circulating air in the cabinet 20. The switch 80 controls the motor circuit to the power mains 86.

50 Preferably, the thermostatic switch 80 is set so that evaporating element 46 will be operated at temperatures which are slightly above that which would be likely to cause the collection of frost or ice therein due to the deposit of moisture from the circulating air in the food storage compartments 30 and 32. If desired, this thermostat may be set so that the condensing element will operate sufficiently to supply refrigerant to the element 46 in such a manner that the operation of the element 46 would allow a slight film of frost to collect thereon during the on-phase of the refrigerating cycle and melt off during the off-phase of the refrigerating cycle. 55 If desired, the thermostatic bulb 82 may be placed in contact with the evaporating element 46 where it will be directly responsive to changes in temperatures within the element 46.

60 In order to insure the circulation of air through the compartments 30 and 32 and about the evaporating element 46, and in order to properly refrigerate said compartments by using a rela-

tively small heat capacity refrigerant evaporating element, I have provided an electrically operated fan 90, which is disposed between the lowermost part of the shell 35 and the element 46 within the passage 44. By this arrangement, 80 the air in the compartments 30 and 32 is circulated in contact with the element 46 whence it passes between the lowermost portions of baffles 38 and the bottom wall 23 of cabinet 20 through the compartments 30 and 32 whence the warm air 85 enters passages 41 and 42 where it is precooled by the refrigerating effect of the evaporating element 34. The element 34 is arranged to cool the metallic shell 35 to a temperature below the temperature of the warm air entering passages 41 90 and 42. The cooling of the shell 35 takes place due to the circulation of air within the shell 35, which circulating air is cooled by the element 34 and contacts with the inner walls of shell 35. The circulating air, after being precooled by the 95 shell 35, is again passed into contact with the element 46 where it is cooled to the desired temperature and recirculated.

100 Preferably, the front wall 26 of the cabinet 20 is provided with separate doors 92, 93 and 94 for gaining access to the compartments 30, 37 and 32, respectively. Access may be had to compartment 37 through openings 96, which are provided in closure plate 36, to permit the insertion and removal of trays 55. The cover plate 36 is also provided with an opening 97 in the lower part thereof to permit the insertion and removal of the drip receiver 49. The opening 97 is closed by door 98.

105 From the foregoing, it will be noted that I have arranged for cooling large spaces for the storage of foods and the like by using a relatively small heat capacity refrigerant evaporator and a fan for circulating the flow of air in the cabinet over said element. It will also be noted that I have provided for freezing large quantities of ice cubes 110 by a relatively large heat capacity refrigerant evaporator, which is isolated from direct contact of the circulating air in the compartments 30 and 32. This avoids the collection of frost and ice on the element 34 due to the deposit of moisture thereon by the circulating air in the compartments 30 and 32. By this arrangement, only that air which is enclosed within the compartment 37 contacts with the element 34. The amount of moisture deposited from this air is such 115 that the element need be defrosted only after a very long period of operation. In the event it is desired to defrost the element 34, I have provided an opening 100 in the bottom wall of the shell 35 adjacent the rear wall 25 of cabinet 20 to 120 permit the defrost water to drain into the passage 44 whence it passes into the receiver 49. Thus, it will be noted that the drip water conductors 48 serve to direct the drip water from both of the 125 elements 34 and 46 into the receiver 49.

130 Although only a preferred form of the invention has been illustrated, and that form described in detail, it will be apparent to those skilled in the art that various modifications may be made therein without departing from the spirit of the 135 invention or from the scope of the appended claims.

140 What I claim as my invention is:

1. Refrigerating apparatus comprising, in combination, a cabinet having a food storage compartment, a refrigerant evaporating element disposed in said cabinet, a metallic shield arranged for isolating said element from direct contact with the circulating air in said compartment, said shield comprising means for precooling the circu- 145 150

- lating air, and a refrigerant evaporating element located below said shield for cooling the circulating air after it has contacted with said shield. 80
2. Refrigerating apparatus comprising, in combination, a cabinet having a food storage compartment, a refrigerant evaporating element disposed in said cabinet, a metallic shield cooperating with a wall of said cabinet for isolating said element from direct contact with the circulating air in said cabinet, baffle means cooperating with a portion of said shield to provide a passage for circulating air, and a refrigerant evaporating element located at one end of said passage for cooling said circulating air. 85
- 10 3. Refrigerating apparatus comprising, in combination, a cabinet having a food storage compartment, a refrigerant evaporating element disposed in said cabinet, a metallic shield cooperating with a wall of said cabinet to enclose said element, a second refrigerant evaporating element disposed in said cabinet below said shield, and a fan for circulating air in said compartment, said fan being disposed between said shield and said second refrigerant evaporating element. 90
- 20 4. Refrigerating apparatus comprising, in combination, a cabinet having a food storage compartment, a refrigerant evaporating element disposed in said cabinet, a shield cooperating with a wall of said cabinet to enclose said element, a pair of baffles vertically arranged and spaced apart on opposite sides of said shield and having their ends spaced from the top and bottom walls of the compartment to provide passages for the circulating air in said compartment, and a refrigerant evaporating element disposed between said baffles for cooling said circulating air. 95
- 30 5. Refrigerating apparatus comprising, in combination, a cabinet having a food storage compartment, a refrigerant evaporating element disposed adjacent the top of said compartment, a refrigerant evaporating element disposed below said first named element, a fan disposed between said elements, a drip receiver positioned below said latter element, and means for directing the drip water from said elements to said receiver. 100
- 40 6. Refrigerating apparatus comprising in combination, a cabinet, a plurality of evaporators in said cabinet, one of said evaporators forming a freezing zone, another of said evaporators providing for cooling circulating air in the cabinet, a shield for preventing circulating air from contacting with the freezing zone, said shield being spaced from the freezing zone and in heat conducting relation between the circulating air and the first mentioned evaporator for precooling the air. 105
- 50 7. Refrigerating apparatus comprising in com- 110
- 55 bination, a cabinet, a plurality of evaporators in said cabinet, one of said evaporators forming a freezing zone, another of said evaporators providing for cooling circulating air in the cabinet, a shield for preventing circulating air from contacting with the freezing zone, said shield being spaced from the freezing zone and in heat conducting relation between the circulating air and the first mentioned evaporator, and means for maintaining a lower temperature in the first mentioned evaporator than the second mentioned evaporator, and a fan for circulating air about said cabinet, said shield and said air cooling evaporator. 115
- 60 8. Refrigerating apparatus comprising, in combination, a cabinet, a plurality of evaporators in said cabinet, one of said evaporators forming a freezing zone, another of said evaporators providing for cooling circulating air in the cabinet, a shield for preventing circulating air from contacting with the freezing zone, said shield being spaced from the freezing zone and in heat conducting relation between the circulating air and the first mentioned evaporator, and means for maintaining a lower temperature in the first mentioned evaporator than the second mentioned evaporator. 120
- 70 9. Refrigerating apparatus comprising, in combination, a cabinet, a plurality of evaporators in said cabinet, one of said evaporators forming a freezing zone, another of said evaporators providing for cooling circulating air in the cabinet, a box-like shield for preventing circulating air from contacting with the freezing zone, said shield being spaced from the freezing zone and in heat conducting relation between the circulating air and the first mentioned evaporator, and means for maintaining a lower temperature in the first mentioned evaporator than the second mentioned evaporator. 125
- 80 10. Refrigerating apparatus comprising, in combination, a cabinet, a plurality of evaporators in said cabinet, one of said evaporators forming a freezing zone, another of said evaporators providing for cooling circulating air in the cabinet, a box-like shield for preventing circulating air from contacting with the freezing zone, said shield being spaced from the freezing zone and in heat conducting relation between the circulating air and the first mentioned evaporator, and means for maintaining a lower temperature in the first mentioned evaporator than the second mentioned evaporator. 130
